UNITED STATES PATENT OFFICE.

JACOB P. KING, OF PHILADELPHIA, PENNSYLVANIA.

ROTARY VALVE.

1,130,521.

Specification of Letters Patent. Patented Mar. 2, 1915

Application filed July 25, 1914. Serial No. 253,300.

To all whom it may concern:

Be it known that I, JACOB P. KING, a citizen of the United States, residing at Philadelphia, in the county of Philadelphia and State of Pennsylvania, have invented certain new and useful Improvements in Rotary Valves; and I do hereby declare the following to be a full, clear, and exact description of the invention, such as will enable others skilled in the art to which it appertains to make and use the same.

This invention relates to rotary valves more particularly designed for use with motor vehicles but capable of use in other relations, and one of the principal objects of the invention is to provide a rotary inlet and exhaust valve of simple construction which will be simple in construction, and reliable and efficient in use.

Another object of the invention is to provide a rotary valve of tapering form, which will be held to its seat by means of a spring, the contour of the valve and seat being such that the wear will be taken up by means of the spring for holding the valve to its seat.

These and other objects may be attained by means of the construction illustrated in the accompanying drawings, in which,

Figure 1 is a side elevation of an engine cylinder and showing a valve in section connected therewith, said valve being made in accordance with this invention, Fig. 2 is a vertical sectional view taken on the line 2-2 of Fig. 1, Fig. 3 is a detail sectional view taken on the line 3-3 of Fig. 1, and Fig. 4 is a sectional view taken on the line 4-4 of Fig. 3.

Referring to the drawing, the numeral 1 designates the engine cylinder having an inlet port 2 for the fuel. Formed on or secured to the cylinder 1 is a valve casing 3 provided with tapering inner walls and an exhaust port 4. A valve 5 is seated in the casing, and the fuel inlet pipe 6 is formed integral with a threaded cap 7 fitted in the upper end of the valve casing 3 by means of the threaded and adjustable flange 8.

The flange 5 is provided with a fuel inlet port 9 and an exhaust port 10, the inlet port leading from the upper edge of the valve down to a point beyond the inlet opening 2 in the cylinder. The exhaust port 10 does not extend quite to the upper edge of the valve, but opens out at the bottom of the valve as shown as 11 in Fig. 3. The upper edge of the valve is provided with a curved

rim or flange 12 which fits the curved portion of the walls of the valve casing 3. A valve stem 13 extends through the valve and is connected near the upper end of the valve centrally of the flange 12 by means of a pin 14. The stem 13 extends through the valve casing and intersects the exhaust port 4. A spiral spring 15 surrounds the valve stem and one end of said spring bears against a collar 16 while the opposite end bears against a boss 17 on the lower end of the valve casing. The spring 15 by expansion serves to hold the valve 5 seated.

Connected to the lower end of the valve stem 13 is a worm gear 18, which is provided with a projecting sleeve having a binding screw 19 extending through the same and into the valve stem. For supporting the valve stem, a projecting finger 20 engages the outer end of the spiral gear 18, said finger being formed on a suitable bracket connected to the crank casing 21. A crank shaft 22 journaled in the crank casing is provided with a spiral 23 which engages and rotates the valve stem 13 through the worm 18. Connected to the lower end of the valve stem 13 is a sleeve 24 provided with a collar 25 formed on a bracket 26 supported upon the crank casing 21 to form a guide for the valve stem. The sleeve 24 is provided with oppositely disposed opened slots 27, and a pin 28 extending through the lower end of the valve stem 13 is movable in the slots 27 to compensate for the wear of the valve 5 in the casing and to permit the spring 15 to hold the valve to its seat.

The lower edge of the valve is provided with a bevel *a* which fits a guide *b* formed in the valve casing.

From the foregoing it will be obvious that owing to the shape of the valve and the operation of the spring 15 and the pin 28, the valve will always be held to its seat and compensate for wear. Another advantage of this construction is that the valve is always accessible for cleaning or repairs, and this valve will operate smoothly and almost noiselessly.

Various changes may be made in the details of construction without departing from the spirit and scope of the invention as defined in the claims.

What is claimed is:

1. A rotary valve comprising a tapering casing, a valve head mounted in the casing and provided with a flange or bead at its

upper edge, said valve head having an inlet opening extending from the upper edge downward, and an exhaust port extending inward at a point below the upper edge of the valve head and opening out into an exhaust port in the casing, means for holding the valve seated, and means for rotating the valve stem and valve.

2. A tapering valve casing, a combined cap and inlet pipe for closing the upper end of said casing, a valve head mounted in the casing, a flange or bead upon the upper end of the valve head for engaging a corre-

sponding surface on the inner wall of the casing, said valve head having a bevel upon its lower end to fit a corresponding bead in the casing, a valve stem connected to said head, said valve head having an inlet and an outlet port, and means for rotating said valve stem.

In testimony whereof I affix my signature in presence of two witnesses.

JACOB P. KING.
